UNITED STATES PATENT OFFICE.

THOMAS WILLIAMS, JR., OF GEE STREET, AND WILLIAM SANGSTER, OF COMPTON BUILDINGS, GOSWELL ROAD, COUNTY OF MIDDLESEX, ENGLAND; SAID SANGSTER ASSIGNOR TO SAID WILLIAMS, JR.

SAUSAGE-STUFFING MACHINE.

SPECIFICATION forming part of Letters Patent No. 276,115, dated April 17, 1883.

Application filed January 5, 1883. (No model.) Patented in England November 17, 1880, No. 4,732

To all whom it may concern:

Be it known that we, THOMAS WILLIAMS, Jr., and WILLIAM SANGSTER, citizens of England, residing, respectively, at Gee Street,

5 Goswell Road, and at Compton Buildings, Goswell Road, both in the county of Middlesex, England, engineers, have invented new and useful improvements in machinery or apparatus for forcing sausage-meat and other 10 substances into skins or other suitable receptacles, (for which we have obtained a patent in Great Britain, No. 4,732, bearing date November 17, 1880,) of which the following is a specification.

15 Our said invention relates to the class of sausage-filling machines wherein a cylinder and a piston or plunger working therein are employed for forcing the meat or other substance into skins or other receptacles; and it 20 consists in the combination, with such machines, of the peculiar arrangement of driving-gear hereinafter described, whereby the piston or plunger is caused to move slowly while forcing out or expelling the contents of 25 the cylinder, and to return by a quick motion to the rear or open end of the cylinder so soon as it has completed its forward traverse, and vice versa, the reversing of its motion and the corresponding change of speed being effected automatically or otherwise at the end 30 of each single stroke of the piston.

The improved machine is by preference arranged so as to be driven by power; but, if desired, it may be worked by hand through the 35 same arrangement of gearing.

And in order that our said invention may be fully understood, we shall now proceed more particularly to describe the same, and for that purpose shall refer to the several figures on 40 the explanatory sheet of drawings hereunto annexed, the same letters of reference indicating corresponding parts throughout all the figures.

Figure 1 of our drawings is a side elevation 45 of our improved filling-machine arranged so as to be self-acting and driven by power. Fig. 2 is a corresponding plan of the same. Fig. 3 is an end elevation corresponding to Fig. 1, and looking on the driving end of the machine;

and Figs. 4, 5, 6, and 7 are details of the driving-gear combined with the said machine for producing the alternate quick and slow motions of the piston or plunger.

A is the bed or base plate of the machine, provided with side standards, B B, for supporting the filling-cylinder C, which is provided with the usual nozzle, D, for receiving the sausage-skin or other receptacle. This cylinder is supported on trunnions E E at its front or delivery end, which rest in suitable 60 bearings in the top of the side standards.

F F are stops for supporting the cylinder in its horizontal or working position, as shown in the drawings, which stops, when the cylinder is in its working position, take their bearing 65 upon the upper edge of the standards B.

G is the piston or plunger working inside the cylinder, as is well understood, and connected with a rack, H, supported and guided by the bearings I, through which it slides freely.

K is the driving-shaft, supported at one end in the bearing L, while its opposite end is supported by and turns freely in a recess, a, in the end of the short shaft M, which shaft works in bearings N N and carries a spur-pinion, M', 75 in gear with the rack H. (Shown more clearly in dotted lines in Fig. 2.) One end of this shaft M is shown in detail section at Fig. 7.

O is the fast driving-pulley, keyed onto the first-motion shaft K.

P is an ordinary loose pulley on the same shaft, and Q is a second loose pulley, which is formed with internal teeth, as hereinafter explained, and serves also as a brake-pulley for the reception of the brake-strap R, worked by 85 the hand or foot lever S.

b is an intermediate spur-wheel mounted upon an eccentric, c, on the driving-shaft K, and gearing into the internal teeth, q', formed inside the loose driving-pulley Q, as shown 90 clearly in the details, Figs. 4 and 5. This intermediate spur-wheel, b, acts as a carrier-wheel, and is made sufficiently broad to engage at the same time with the teeth t of the internal-toothed wheel T, fast on the end of 95 the shaft or spindle M. (See Fig. 2 and details, Figs. 6 and 7.)

We do not confine or restrict ourselves to

the precise number or proportions of teeth shown in our drawings in the before-mentioned arrangement of driving-gear, as the proportions may be varied; but those shown will be found to give a good result—namely, say ten teeth in the intermediate spur-wheel, *b*, thirteen teeth in the loose internal-toothed brake-pulley *Q*, and twelve teeth in the internal-toothed wheel *T*.

- 10 *U* is a sliding rod (which may be used when the machine is to work automatically) sliding in suitable guides, and connected by a stud or pin, *V*, or otherwise, with a slot in the end of one of the arms of the horizontal bell-crank lever *W*, the other arm being connected, as shown clearly in Fig. 3, by a similar stud or pin, or its equivalent, with a horizontal slide, *X*, working in guides *Y*. Through a slot in this slide passes the upright weighted lever or strap-shifter *Z*, carrying the fork or strap-guide *d*.

In commencing to work the machine the cylinder is first charged with meat or other substance, the driving-strap being on the pulley *O*. The attendant then applies the brake *R*, whereupon a slow motion is transmitted from the fast pulley *O*, through the shaft *K*, intermediate spur-wheel, *b*, internal stationary toothed pulley *Q*, and internal-toothed wheel *T*, to the shaft *M* and spur-pinion *M'*. The rack *H* and piston *G* will then commence to move slowly inward, the speed of the spur-pinion *M'* being reduced to about one revolution to twelve of the driving-shaft *K*, as the intermediate spur-wheel, *b*, on the eccentric *c* is caused to travel or gyrate round the circle of internal teeth in the pulley *Q* and internal-toothed wheel *T* simultaneously, and also to revolve round the said rotating eccentric, but in a reverse direction to that of the eccentric and shaft *K*. Just before the piston has arrived at the front or delivery end of the cylinder the arm *e* on the end of the rack *H* pushes the sliding rod *U* inward, thereby moving the bell-crank *W*, slide *X*, and lever *Z* into the reverse position to that shown in Fig. 2, and consequently shifting the driving-strap from off the driving-pulley *O* onto the loose internal-toothed pulley *Q*, the brake-strap on the said pulley being at the same time released by the attendant, so as to allow the pulley *Q* to rotate freely, while the shaft *K* may remain stationary. A quick rotary motion (in the reverse direction to that previously obtained) is by this adjustment transmitted from the internal-toothed pulley *Q*, through the intermediate spur-wheel, *b*, direct to the internal-toothed wheel *T*, fast on the shaft *M*, which carries the spur-pinion *M'*, the intermediate spur-wheel, *b*, revolving freely round the eccentric *c* as a center and serving as a carrier-wheel. The result is a quick return motion of the rack *H* and piston *G*. Just as the piston is emerging from the

rear or open end of the cylinder it pushes the rod *U* outward, and brings the bell-crank lever *W* and slide *X*, with the weighted strap-shifting lever *Z*, into the positions shown in Figs. 2 and 3, thereby shifting the driving-strap by the action of the fork *d* from the loose pulley *Q* back again onto the fast driving-pulley *O*. The slow forward motion of the piston or plunger *G* can be instantly arrested at any moment by simply releasing the brake *R*. A lever-arm, *f*, actuated by the upright handle *g*, serves to turn up the mouth of the cylinder into the position shown by dotted lines in Fig. 1, for the purpose of facilitating the introduction of a further charge of sausage-meat or other substance therein, after which the cylinder is lowered to its original horizontal position and the machine is started again.

The trunnions *E* and their bearings are by preference so shaped as to constitute stops for preventing the cylinder from being accidentally turned beyond a vertical position.

What we claim, and desire to secure by Letters Patent of the United States, is—

1. The combination of the shaft provided with the fixed internally-toothed wheel, the shaft provided with the eccentric and the loose internally-toothed pulley, the spur-wheel mounted on the eccentric and meshing with the toothed pulley and wheel, a brake-strap for alternately holding the toothed pulley fixed and then permitting it to turn, and means for imparting motion to the shafts, whereby the several parts will operate substantially as set forth.

2. In a sausage-filling machine, the combination of cylinder *C*, mounted on trunnions, and piston *G*, carrying the rack *H*, with the short shaft *M*, carrying the spur-wheel *M'*, and internal-toothed wheel *T*, the first-motion shaft *K*, carrying the driving-pulley *O*, internal-toothed brake-pulley *Q*, and intermediate spur-wheel, *b*, mounted on the eccentric *c*, the brake-strap *R*, and the lever *S*, all substantially as specified.

3. The two shafts provided with the internally-toothed wheel and pulley meshing with the spur-wheel mounted on the eccentric, in combination with the piston-rack provided with an arm, the rod and the slide connected by the bell-crank lever, and the belt-shifter acted on by the slide, the several parts being arranged to operate as set forth.

In witness whereof we have signed our names in the presence of two subscribing witnesses.

THOMAS WILLIAMS, JR.
WILLIAM SANGSTER.
